UNITED STATES PATENT OFFICE.

JESSIE R. BURN, OF SAN ANTONIO, TEXAS.

DESIGN FOR A CARD-TABLE-COVER CLAMP.

Application filed May 31, 1928. Serial No. 26,934. Term of patent 14 years.

To all whom it may concern:

Be it known that I, JESSIE R. BURN, a citizen of the United States, residing at San Antonio, in the county of Bexar and State of Texas, have invented a new, original, and ornamental Design for a Card-Table-Cover Clamp, of which the following is a specification, reference being had to the accompanying drawing, forming part thereof.

Figure 1 is a perspective view, and
Fig. 2 is a top plan view, of a card table cover clamp embodying my design.

I claim:
The ornamental design for a card table
cover clamp, as shown.
